UNITED STATES PATENT OFFICE.

WILLIAM H. FAUBER AND HAZEL L. FAUBER, OF BROOKLYN, NEW YORK.

GAME DEVICE.

Application filed July 23, 1925. Serial No. 45,563.

To all whom it may concern:

Be it known that WILLIAM H. FAUBER and HAZEL L. FAUBER, citizens of the United States, and residents of borough of Brooklyn, in city of New York, in the county of Kings and State of New York, have invented certain new and useful Improvements in Game Devices, of which the following is a specification.

10 This invention relates to educational or amusement apparatus or devices of the kind having relatively rotary members provided with characters and pointers for selecting the characters, though it is noted that the 15 invention is not limited to either educational or amusement devices, nor in some respects even to selecting characters.

One object of the invention is to provide a simple fascinating, light weight, true-running ball bearing game spinner or other device of this kind suitable for commercialization by manufacturers for the instruction of children in letters, numbers, colors or other mental training; and which may be manufactured at a minimum of cost.

Another object of the invention is to provide an apparatus or device of this kind which has a plurality of pointers and character bearing members some remaining stationary and others adapted for unconstrained movement at different speed giving a number of selective results at one operation.

Other objects of the invention are to improve generally the simplicity and fascination of such devices and to provide a device or apparatus of this kind which is durable, extremely economical to manufacture and simple to operate and which will not get 40 out of order.

Still other objects of the invention will appear as the description proceeds; and while herein details of the invention are described and claimed, the invention is not limited to these since many and various changes may be made without departing from the scope of the invention as claimed in the broader claims.

50 The inventive features for the accomplishment of these and other objects are shown herein in connection with an improved ball

bearing game spinner which, briefly stated, includes an upper bearing plate rotatably mounted above a lower bearing plate mounted on a base having characters thereon. Bearing balls between said plates are spaced by a rotary auxiliary plate provided with openings receiving the balls. Secondary balls support the auxiliary plate and are spaced by a ring having openings furnishing transverse edges resting on the secondary balls. Disks mounted on said upper plate and auxiliary plate are also provided with characters near those of the base; and pointers carried by said ring and auxiliary plate cooperate with said characters.

In the accompanying drawing, showing by way of example, several of many possible embodiments of the invention,

Fig. 1 is a fragmental plan showing one 70 form of the device;

Fig. 2 is a central vertical sectional view, said section being taken on the line A—A of Fig. 1;

Fig. 3 is a fragmental plan showing one 75 form of the secondary balls and their spacing ring;

Fig. 4 is a transverse vertical sectional view, said section being taken on the line a—a of Fig. 1;

Fig. 5 is a vertical sectional view, taken on the line b—b of Fig. 1;

Fig. 6 is a vertical sectional view, said section being taken on the line c—c of Fig. 1;

Fig. 7 is a fragmental central vertical sectional view showing another form of the invention; and

Figs. 8 and 9 are radial vertical sectional views showing the bearings of other forms of the invention.

The various parts of the apparatus are carried on a support or container comprising side walls 10 and a bottom board or base 11 of wood, sheet metal, cardboard or other suitable material, said base being provided with a central opening 12 (Fig. 2) receiving therein a tubular pivot post 13 fixedly mounted in the opening and receiving thereon identically shaped upper and lower circular sheet metal bearing plates 15 and 16 100 respectively provided with stamped bosses 17, 18 surrounding central openings larger than

and received over said post. Said plates are also respectively provided with stamped annular ribs 20, 21 near the periphery of the plate leaving flat margins 22, 23. The plates 5 15 and 16 being identical may be made by the same dies and used interchangeably.

The lower plate 16 rests on said base 11 and has its rib 21 and boss 18 upwardly disposed, the upper plate having its rib 20 10 and boss 17 downwardly disposed and slightly spaced from the rib and boss of the lower plate to receive an auxiliary or spacing plate 25 disposed between said bearing plates almost in contact with said ribs, and provided 15 with a large central opening received on said post, and three openings 26 loosely receiving and spacing three main supporting bearing balls 27 disposed substantially equal angles apart between the margins 22, 23 of said 20 plates.

Three secondary bearing balls 30 resting on the margin 23 of the lower plate and engaging in a groove 31 of the spacing plate 25 substantially equal angles apart support 25 the spacing plate just out of contact with said ribs 20, 21. An inverted trough shaped sheet metal spacing ring 34 under said groove 31 is provided at the upper part with three transverse slots 35 (Fig. 3) furnishing 30 transverse bearing edges 36 between which is received the upper part of the secondary bearing balls 30 for holding them spaced apart.

A thimble 38 (Fig. 2) loosely received in 35 said central openings and on said post is provided with lateral end flanges 39, 40 engaging over said bearing plates to hold all of said plates 15, 16 and 25; ring 34 and balls 27 and 30 from falling apart.

40 A top disk 45 is mounted on said upper bearing plate 15 and has a central opening loosely receiving said post 13; and an auxiliary annular disk 46 is removably mounted on the margin of said spacing plate 25 and 45 projecting a distance beyond the top disk. Radial division lines 47, 48, 49 (Fig. 1) disposed equal angles apart along the margins of said disks and the adjacent portion of the base form character receiving spaces there- 50 between in which are placed numerals 50, 51, 52 or other desired characters.

The ribs 20, 21 being very close to the auxiliary plate, engage with the latter to prevent the denting or distortion of the 55 bearing plates by the balls, should a player lean or bear too heavily on the top disk.

Pointers 54 and 55 removably received on extensions 56 and 57 of the auxiliary plate and spacing ring and have their points 58 60 disposable to indicate said characters 50 of the base. Each point comprises a wide inner end portion 59 received against a face of the extension 56 or 57, and lateral flanges 60 on said portions frictionally engaging 65 over the opposite face of the extension.

A U-shaped clip pointer 61 (Figs. 1 and 6) is adjustably removably clasped on the margin of said auxiliary disk and has its point 62 disposable adjacent to character spaces of the top disk.

70 The pointers 54, 55 and 61 in addition to their points as above described, are respectively provided with longitudinal indicating lines 65^a, 65^b, 65^c; whereby the pointer 54 may cooperate with both characters 50 and 52, pointer 55 may cooperate with characters 50 and 51, and the pointer 61 may cooperate with characters 50 and 52.

75 The upper, lower and auxiliary plates 15, 16 and 25 are respectively provided with 80 very slightly raised radial ribs 65, 66 and 67 (Figs. 1 and 5) engageable with all of said balls and positioned to prevent said points from stopping on a division line. The showing of these ribs is very much exaggerated 85 in Fig. 5, as the amount of projection is hardly perceptible, but is sufficient to keep the ball from stopping directly on the rib. The ribs 65 control the pointers 54 and 61 90 relative to the top disk 45; the ribs 67 control the pointer 55 relative to the auxiliary disk 46; while the ribs 66 control the pointer 55 relative to the characters 50 on the base.

95 The operation of the apparatus as described is very simple. The top disk 45 is 100 spun by engagement or striking the edge or top face with the fingers moving in the direction of rotation. This causes the balls 27 and, therefore, the spacing plate 15, the disk 46 and pointers 54 and 61, to move at substantially half the angular speed of the top disk. This, in turn, causes the ring 34 and pointer 55 to move at substantially one-fourth the speed of the top disk. When the disks and associated parts come to rest, 105 various numbers are pointed out by the various pointers.

110 If the disk 46 be not removed, each operation of the apparatus will give four readings as follows:

1. A number 50 indicated by the pointer 55;
2. A number 51 indicated by the pointer 55;
3. A number 52 indicated by the pointer 61; and
4. A number 50 indicated by the pointer 61.

115 If the disk 46 be removed, each operation will give readings as follows:

1. A number 50 by the pointer 55;
2. A number 50 by the pointer 54; and
3. A number 52 by the pointer 54.

120 Any game now played by the usual known game spinners may be played with this device; but because of the larger number of readings possible with this device, a much greater variety of games, including educational games may be played with it than with the usual known game spinners.

125 While a vast number of simple and complicated games and the like, both old and yet to be devised, may be played with the 130

herein device, this number is too great to describe or catalogue here, and only one of the simplest educational games is here described as follows:

5. Two players, for instance arithmetic pupils, take turns in spinning the device. With the disk 46 not removed, each operation will give four numbers, which may be set down as multi digit numbers for the respective 10 players. After a predetermined number of operations, each player adds up his numbers, the one finishing first adding a bonus for speed. From the totals, penalties may be deducted for errors to get a final score. This 15 operation is repeated until a predetermined amount, fixed upon as "game," is first arrived at. Should the disk 46 be not removed, three to six column numbers would be used.

In the form of invention of Fig. 7, the 20 combined upper bearing plate and top disk 15^a is disposed above the bottom or on the base 11^a of a round or square sheet metal box. An auxiliary plate 25^a between said base and disk is provided with an upwardly and outwardly inclined portion 31^a provided with openings 26^a receiving and spacing the balls 27^a supporting the disk. The extreme periphery of the auxiliary plate is formed with a downturned annular flange 46^a almost 25 in contact with said base and plate to prevent distortion of the disk and base, as previously explained. Said auxiliary plate 25^a may be provided with a pointer 55^a to cooperate with the characters of the base and top disk. The plates 15^a and 25^a are loosely received on the post 13^a mounted in an opening in the base 11^a.

In the form of invention shown in Fig. 40 8 an upper plate 15^b is disposed above a lower plate 16^b on the base 11^b. An auxiliary plate 25^b between said plates spaces the balls 27^b supporting the upper plate. Secondary balls 30^b supporting the auxiliary plate 25^b are spaced by a secondary disk 34^b 45 having openings 35^b receiving the secondary balls. A top disk 45^b is disposed on said upper plate; and a disk 46^b carried by said auxiliary plate 25^b may carry a clip pointer 61 to cooperate with the characters of the 50 base and top disk.

In the form of invention of Fig. 9, an upper plate 15^c is disposed above a lower plate 16^c on the base 11^c. An auxiliary ring 25^c 55 between said plates spaces the balls 27^c engaging in grooves 20^c, 21^c and supporting the upper plate. Said ring being almost in contact with the plates, serves to prevent distortion, as explained and may carry a pointer 55^c to cooperate with characters on the base 11^c and top disk 45^c.

We claim as our invention:

1. In combination, a lower member; an upper plate above said lower member; ball bearings between said member and plate; an auxiliary plate spacing said bearings; a

disk on said upper plate having characters; and a pointer cooperating with said characters.

2. In combination, a base; a lower bearing plate on said base; an upper bearing plate above said lower plate; ball bearings between said plates; an auxiliary plate spacing said bearings; secondary ball bearings supporting said auxiliary plate; and a disk carried on said upper plate.

3. In combination, a lower bearing member; an upper bearing plate above said lower member; ball bearings between said plate and member; an auxiliary plate for spacing the balls; a disk carried by one plate and having characters; and a pointer on the other plate cooperating with the characters.

4. In combination, a base; a lower plate on said base; an upper plate above said lower plate; balls between said plates; an auxiliary plate between said bearing plates for spacing the balls; a top disk on said upper plate; characters on said disk; and a pointer carried by said auxiliary plate and cooperating with said characters.

5. In combination, a lower bearing member; an upper bearing plate above said lower member; balls between said member and plate; an auxiliary plate spacing said balls; and disks carried on said plates.

6. In combination, a base; a lower plate on said base; and upper plate above said lower plate; bearing balls held between said plates; a top disk on said upper plate; characters on said disk; and a pointer cooperating with said characters.

7. In combination, a base; a lower sheet metal bearing plate on said base; an upper sheet metal bearing plate above said lower plate; ball bearings between said bearing plates; a disk on said upper plate having characters thereon; and a pointer associated with said characters.

8. In combination, a thin bearing plate; a thin upper bearing plate above said lower plate; a disk on the upper plate; ball bearings between said plates; and means for holding said plates against distortion.

9. In combination, a thin lower bearing plate; a thin upper bearing plate above said lower plate; ball bearings between said plates; and annular means near said balls for holding said plates spaced to prevent distortion of the plates.

10. In combination, a base; a lower bearing plate on said base; an upper bearing plate above said lower plate; a disk on the upper plate; widely spaced ball bearings between said plates; and annular ribs on the plates pressed toward each other nearly into contact with each other.

11. In combination, a base; upper and lower bearing plates each provided with an annular rib; the lower plate resting over said base and having its rib upwardly dis-

- posed, the upper plate having its rib downwardly disposed; bearing balls between said plates; an auxiliary plate between said ribs provided with spacing openings receiving the balls; a top disk on said upper bearing plate; characters along the margins of said disk; and a pointer cooperating with said characters.
12. In combination, a base; a lower bearing plate on said base; an upper bearing plate above said lower plate; a disk on the upper plate; balls between said bearing plates; an auxiliary plate for holding said balls spaced apart; three balls for supporting the auxiliary plate; and means for holding said three balls widely spaced apart.
13. In combination, a base; a lower bearing plate on said base; an upper bearing plate above said lower plate; a disk on the upper plate; three bearing balls between said plates; and a plate for holding said balls widely spaced apart.
14. In combination, a base; a circular lower plate on said base having a raised central portion and a raised annular rib near the periphery; a rotary circular upper plate above said lower plate having a depressed central portion and marginal rib; said plates being of identical shape and configuration and interchangeable the one for the other; bearing balls between said plates; a top disk on said upper plate; characters on said disk; and a pointer cooperating with said characters.
15. In combination, a base; a lower bearing plate on said base; a disk above said lower plate; ball bearings between said plate and disk; an auxiliary plate spacing said bearings; secondary ball bearings supporting said auxiliary plate; and means spacing said secondary balls.
16. In combination, a base; a lower plate on said base; an upper plate above said lower plate; balls between said plates; an auxiliary plate between said bearing plates for spacing the balls; secondary balls supporting the auxiliary plate; a ring resting on the secondary balls; a top disk on said upper plate; characters on said disks and base; and pointers carried by said ring and auxiliary plate and cooperating with said characters of the base.
17. In combination, a base; upper and lower bearing plates; bearing balls between said plates; an auxiliary plate between said bearing plates provided with spacing openings receiving the balls, and an up-pressed groove; secondary bearing balls engaging in said groove and resting on the lower plate; a ring provided with transverse bearing edges resting on the secondary balls; a top disk on said upper bearing plate; an annular disk on the spacing plate and projecting beyond the top disk; characters along the margins of said disks and the adjacent portion of the base; and pointers carried by said auxiliary plate ring cooperating with said characters of the base.
18. In combination, a base having characters thereon; a rotary top disk having characters thereon; a rotary auxiliary plate between said base and disk; a rotary ring; and pointers mounted on the auxiliary plate and ring cooperating with the characters of the disk and base.
19. In combination, a base; a lower plate on said base; balls on said plate; an auxiliary plate spacing the balls; secondary balls supporting the auxiliary plate; characters on the base; and pointers carried by said ring and auxiliary plate and cooperating with the characters.
20. In combination, a base; a lower bearing plate on said base; an upper bearing plate above said lower plate; ball bearings between said plates; an auxiliary plate between said bearing plates and spacing said bearings; secondary ball bearings supporting said auxiliary plate; and a ring spacing said secondary balls; a disk on the upper plate; and pointers on the auxiliary plate and ring cooperating with the disk.
21. In combination, a base; a rotary top disk; a rotary auxiliary plate between said base and disk; and a pointer removably mounted on the auxiliary plate and cooperating with the disk and base.
22. In combination, a base; a rotary top disk; a rotary auxiliary plate between said base and disk; and an auxiliary disk removably mounted on the auxiliary plate.
23. In combination, a base; a rotary top disk; a rotary auxiliary plate between said base and disk; an auxiliary disk removably mounted on the auxiliary plate; and a clip removably mounted on the edge of the auxiliary disk and cooperating with the top disk.
24. In combination, a base having characters thereon; a rotary top disk having characters thereon; a rotary auxiliary plate between said base and disk; a disk removably mounted on the auxiliary plate; and a pointer removably mounted on the auxiliary plate and cooperating with the characters of the disks and base.
25. In combination, a base; a lower bearing plate on said base; an upper bearing plate above said lower plate; ball bearings between said plates; an auxiliary plate between said bearing plates and spacing said bearings; a disk on the upper plates; and a disk and a pointer removably carried on the auxiliary plate.
26. In combination, an upper disk having characters thereon; a lower disk; and a U-shaped clip pointer adjustably removably clasped on the margin of said lower disk and

having its point disposable adjacent to character spaces of the upper disk.

27. In combination, a base; a lower bearing plate on said base; a disk on the upper plate; an upper bearing plate above said lower plate; ball bearings between said plates; each of said plates having a central opening; and a post mounted on the base and loosely received in the openings.

10 28. In combination, a base; a lower bearing plate on said base; a disk on the upper plate; an upper bearing plate above said lower plate; ball bearings between said plates; and means for preventing the separation of the balls and plates.

15 29. In combination, a base provided with a central opening; a tubular pivot point mounted in said opening; upper and lower bearing plates each provided with a central opening larger than and received on said post, a stamped boss surrounding said opening, and a stamped annular rib near the periphery of the plate; the lower plate resting on said base and having its rib and boss upwardly disposed, the upper plate having its rib and boss downwardly disposed and slightly spaced from the rib and boss of the lower plate; bearing balls disposed between said margins; an auxiliary disposed between said ribs almost in contact with the ribs, and provided with a central opening received on said post, three spacing openings loosely receiving and spacing the balls; a thimble loosely received in said central openings and on said post and provided with lateral flanges engaging over said bearing disks to hold all of said plates, ring and balls together; a top disk mounted on said upper bearing plate and having a central opening loosely receiving said post; and an annular disk removably mounted on the margin of the auxiliary plate.

35 30. In combination, a base; a lower bearing plate on said base; an upper bearing plate above said lower plate; ball bearings between said plates; an auxiliary plate between said bearing plates and spacing said bearings; secondary ball bearings supporting said auxiliary plate; a ring spacing said secondary balls, and having slightly downwardly projected radial ribs; a disk on said auxiliary plate having characters thereon and divisions therebetween corresponding to said ribs; and a pointer on the ring co-operating with the characters of the disk.

45 31. In combination, a base having radial divisions and characters therebetween; a lower bearing plate on said base and having slightly up-pressed radial ribs corresponding to said divisions; an upper bearing plate above said lower plate; a disk on said upper plate; ball bearings between said plates; an auxiliary plate spacing said bearings; secondary balls supporting said auxiliary

50 plate and engageable with the ribs of the lower plate; and a ring spacing said secondary balls; and a pointer on the ring cooperating with the characters of the base.

32. In combination, a base having radial divisions and characters therebetween; a lower bearing plate on said base and having slightly raised radial ribs corresponding to said divisions; an upper bearing plate above said lower plate and having slightly downwardly projected radial ribs; a disk on said upper plate having divisions corresponding to said down-pressed ribs and characters therebetween; ball bearings between said plates and engageable with said ribs of both plates; an auxiliary plate between said bearing plates and spacing said bearings; and a pointer on the auxiliary plate cooperating with the disk characters of the disk and base.

55 33. In combination, a pair of rotary members; a disk on one member having characters thereon; a pointer on the other member cooperating with said characters; and means for preventing the stopping of the pointer midway between adjacent characters.

34. In combination, a pair of rotary plates spaced from each other; bearing balls engaging said plates; a disk on one plate having characters thereon; a pointer on the other plate cooperating with said characters; and radial ribs on one plate for engaging the balls to prevent the stopping of the ball midway between characters.

60 35. In combination, a bearing plate having radial ribs thereon; a bearing member spaced from said plate; bearing balls between said plate and member; an auxiliary plate spacing said bearings; a disk on one plate having characters thereon and radial divisions therebetween corresponding to said ribs; and a pointer on the other plate cooperating with said characters.

36. In combination, a base; a rotary member mounted on the base; an auxiliary member between said member and base; means carried entirely between said rotary member and base for causing one member to influence the other member to rotate; and a pointer carried by one of said members and co-operating with the other.

65 37. In combination, a base; a rotary disk mounted on the base; an auxiliary disk between said base and upper disk; and means carried entirely between said rotary disk and base for causing one disk to influence the other member to rotate.

70 38. In combination, a base; an upper rotary disk spaced slightly above said base; an auxiliary rotary disk between said base and upper disk; and means carried mainly between said upper disk and base for causing one disk to influence the other disk to rotate at a different speed.

- 8
39. In combination, a base; a rotary member mounted on the base; rolling bearings between said member and base; a member spacing said bearings; and a pointer carried by one of said members and cooperating with the other member.
40. In combination, a pair of spaced coaxial relatively rotary members; rolling bearings between said members; an auxiliary member spacing said bearings; and an indicator carried by the auxiliary member and cooperating with another member.
- 10

41. In combination, a pair of spaced coaxial rotary disks; and a pointer adjustably mounted on and carried by one disk to travel therewith and adapted for adjustment to different positions therearound and cooperating with the other disk.

Signed at New York in the county of and State of New York this 20th day of July 1925.
